United States Patent Office.

PHILANCY D. TIFFT, OF EAGLEVILLE, OHIO.

Letters Patent No. 102,989, dated May 10, 1870; antedated May 3, 1870.

IMPROVEMENT IN WARP-STAND FOR LOOM.

The Schedule referred to in these Letters Patent and making part of the same.

To all whom it may concern:

Be it known that I, PHILANCY D. TIFFT, of Eagleville, in the county of Wood and in the State of Ohio, have invented certain new and useful Improvements in Warp-Stands; and do hereby declare that the following is a full, clear, and exact description thereof, reference being had to the accompanying drawings and to the letters of reference marked thereon making a part of this specification.

The nature of my invention consists in the construction and general arrangement of a warp-stand to be placed in front of the loops.

In order to enable others skilled in the art to which my invention appertains to make and use the same, I will now proceed to describe its construction and operation, referring to the annexed drawings, in which—

Figure 1 is a side elevation, and

Figure 2, a plan view of my machine.

A represents the stand or frame, resting on suitable legs, having casters underneath, so that it can be moved readily wherever wanted.

This stand is made in the shape of a box, having two lids, B B, hinged to the stand and folding outward, as seen in the drawings.

One of these lids is provided with a guide, D, for holding the front ends of the wire plates C C, which contain the bobbins or quills. The other lid is provided with a series of buttons, E E, for holding the back ends of the wire plates C C. Any desired number of plates may be put on the stand, as needed.

On the guide D is placed a series of upright wire guides or loops, a a, through which is passed a rod, G, for keeping the warp and bobbins in place while placing the harness and reed in the loom.

In front of the guide D, near the outer end of the lid, is secured a grooved block, F, in which the reed J is placed.

On the sides of the stand A are placed slides I, on the outerends of which are placed the holders or guides H H for the harness K.

The stand thus constructed is to be placed in front of the loom, the harness and reed put in the loom, the warp tied to the stick on warp-roller and drawn on, then tied to the stick on the cloth-roller, and it is ready to work.

When the warp is drawn off the stand, the wire or bobbin-plates C C are to be placed inside the stand; the harness-holders or guides H H also inside the stand; the slides I I moved back even with the stand, and the stand shut up.

Having thus fully described my invention,

What I claim as new, and desire to secure by Letters Patent, is—

1. The stand A, provided with outwardly-folding lids B B, and with the slides I, supporting the harness-holders or guides H, substantially as herein set forth.

2. The wire or bobbin-plates C C, held on the lids B B by means of the guide D and buttons E E, substantially as shown and described.

3. The combination and arrangement of the stand A, lids B B, plates C C, buttons E E, guide D, rod G, slides I I, and harness-holders or guides H H, all constructed substantially as and for the purposes herein set forth.

In testimony that I claim the foregoing, I have hereunto set my hand this 9th day of September, 1869.

P. D. TIFFT.
